TRAFFIC APPLIANCE

Henry W. Dodson, St. Louis, Mo.

Application April 26, 1939, Serial No. 270,083

3 Claims.

(Cl. 88—78)

The present invention relates generally to traffic devices, and more particularly to that type of traffic device which is multi-directional in its operation.

An object of the present invention is to provide a novel multi-directional traffic device, which is adapted to be disposed at an intersection to control the traffic from all routes moving thereto.

Another object is to provide a traffic safety device for motor or pedestrian traffic to reduce accidents.

Another object is to provide a multi-directional traffic signal constructed to permit the driver of a car moving into an intersection to view the cross traffic and the traffic in the rear.

Another object is to provide a multi-directional traffic signal which includes means for defining the curbing intersections and other hazards.

Another object is to provide a traffic signal which includes reflective means to assist a motorist in the observation of both cross and rear traffic.

Another object is to provide a multi-directional traffic signal which has a circumferential reflecting surface which assists an approaching driver in determining the location of other traffic and which has means for illuminating curbing intersections.

Another object is to provide a multi-directional traffic signal which is adapted to fulfill all of the objects and advantages sought therefor.

Other objects and advantages will be apparent from the following description, taken in conjunction with the accompanying drawings, in which:

Fig. 1 is a side elevation of a traffic signal constructed in accordance with the teachings of the present invention;

Fig. 2 is a section on the line 2—2 of Fig. 1;

Fig. 3 is a bottom view of the traffic signal shown in Fig. 1;

Fig. 4 is a section on the line 4—4 of Fig. 2;

Fig. 5 is a fragmentary section through a swivel joint employed to support certain adjustable mirrors;

Fig. 6 is a section on the line 6—6 of Fig. 2;

Fig. 7 is a section on the line 7—7 of Fig. 6;

Fig. 8 is a section on the line 8—8 of Fig. 4;

Fig. 9 is a section on the line 9—9 of Fig. 4;

Fig. 10 is a fragmentary section taken along the line 6—6 of Fig. 2, the canopy, mirror and hazard light being shown in adjusted positions;

Fig. 11 is a fragmentary section taken on the

line 1—1 of Fig. 6, the adjustable elements being in the positions of Fig. 10;

Fig. 12 is a modification of the traffic signal shown in Fig. 1;

Fig. 13 is a diagrammatic view showing a preferred disposition of the present traffic signal; and,

Fig. 14 is a diagrammatic view showing another disposition of a modified traffic signal.

10 Referring to the drawings more particularly by reference numerals, 20 designates a multi-directional traffic signal constructed in accordance with the concepts of the present invention. The traffic signal 20 is adapted to be suspended above the street in a position to control the traffic moving into the intersection. A bisectional shaft 21 includes an upper section 22 and a lower section 23 which are connected by a juncture box 24 (Fig. 1). The upper section 22 terminates at its free end in an eye 25 which receives supporting elements 26 connected to some suitable support (not shown).

15 At the free end of the lower section 23 is a housing 28 (Fig. 4) having a flange 29. The housing 28 may be integral with or connected to the free end of the lower section 23. A supporting member 30 has an inner circular segment 31 fixed to the flange 29 by screws 32, or the like. The member 30 includes an outer octagonal segment 34 connected to the inner segment 31 by suitable spokes 35.

20 A reflector 36 is connected to the segment 31 by screws 37, or the like, and surrounds a globe 38 connected to the housing 28. Within the globe 38 is a bulb (not shown) which is secured in a socket (not shown) disposed in the housing 28.

25 The outer segment 34 supports a plurality of reflectors 39 and 40 which are transparent mirrors. Each of the reflectors 39 and 40 is received by a member 41 and 42, respectively, each of which is of a configuration to provide channels to receive the lower edge and the end edges of the respective reflector.

30 A universal connection 43 including a socket member 44 secured to the member 41 and a ball member 45 secured to the outer section 34 adjustably supports each reflector 39. A turn buckle member 46 is pivotally connected to each vertical channel of the member 41 towards the upper edge of the reflector 39 at one end, and pivotally connected at the other end to a collar 48 which is adjustably secured by set screws 49, or the like, to the shaft 23 (Fig. 4). Each member 41 includes a central casing section 50 which is adapted to receive signs 51, or the like. Leads

53 extend from within the casing section 50 and pass through a suitable opening in the housing 28 and into the shaft 23.

Each member 42 is adjustably supported on the outer segment 34 by a hinge 55. A turn buckle member 56 is pivotally connected to a projection 57 connected to the upper edge of the member 42 centrally thereof at one end, and at the other end pivotally connected to a collar 58 secured by set screws, or the like, to the shaft 23. The member 42 includes a casing section 59 adapted to receive traffic lights 60, 61, and 62 in vertical relation (Figs. 1 and 6). The traffic lights 60, 61, and 62 are disposed behind the transparent mirror reflectors 40. Suitable leads 63 which extend through the casing section 59 and through suitable openings into the housing 28 provide electrical connections between the traffic lights 60, 61, and 62 and a control (not shown).

A spot light 64 is pivotally connected by a hinge 65 to the outer segment 34 beneath each reflector 39 and 40. A link 66 is pivotally connected at one end to each light 64 and at the other end to a second link 67. The link 67 is adjustably secured by means of a connection 68 to a shaft 69 which is fixed to a collar 70 adjustably secured to the shaft 23 by set screws 71, or the like. The connection 68 includes an integral sleeve 73 (Figs. 8 and 9) which receives the shaft 69 and a threaded stem 74 which extends through an enlarged portion 75 of the link 67 and receives a nut 76 and a washer 77 to bind the link 67 and connection 68 in selected relationship. A set screw 78, or the like, is employed to secure the connection 68 relative to the shaft 69. A lead 80 which passes from each light 64 into the housing 28 electrically connects each light 64 with a suitable switch mechanism (not shown).

A canopy 82 of the octagonal configuration shown is adjustably connected to the shaft 23 through an integral collar 83 and set screws 84.

Street signs 85 may be connected to the shaft 23 by suitable collar brackets 86 which are adjustably secured to the shaft. Stop signs, and the like, may also be mounted on the shaft 23.

A cable 87 is shown extending from the juncture box 24. The cable 87 includes the numerous electrical leads which extend through the shaft 23. It is to be understood, of course, that the various leads are suitably connected to operating switches.

There is shown in Fig. 12 a modified traffic signal 90 which differs from the traffic signal 20 in that it includes a pedestal base 91 as a support. The base 91 includes a weighted section 92 and a shaft 93 which is connected to the shaft 23'. The electrical leads (not shown) of the several electrical devices are led away underground to suitable switches, the weighted section 92 including a channel for the passage of such electrical leads. The reflector 38 and associated bulb of the traffic signal 20 are omitted from the traffic signal 90. The traffic signal 90 otherwise is the same as the traffic signal 20 and, therefore, further description thereof is unnecessary.

The present traffic device may be constructed without signal lights, in which event it functions as a safety device to reveal otherwise hidden traffic. The reflective surfaces are amber clear mirrors when the device is not equipped with signal lights. When constructed without signal lights, the device is particularly adapted for use in passageways to assist the movement of individuals. The narrow intersecting passageways

of hotels, and other structures, are relieved of hazards through the use of the device.

The present device is, therefore, quite flexible as to use and construction.

5 It is to be understood, of course, that the various elements and working parts of the traffic signal are to be constructed of suitable material and are to be of suitable configuration. Both the hinges 55 and the hinges 65, which respectively 10 mount the reflectors 40 and lights 64, may be replaced by universal connections such as the connection 43 (Fig. 5), if preferable. The particular turn buckle members and other adjustable connections may be varied as the remaining construction demands.

Operation

The traffic signal 20 is adapted to be suspended at an intersection as shown in Fig. 13. The traffic signal 90 would, of course, be located similarly. It is evident that, with the traffic signal 20 controlling an intersection such as that shown in Fig. 13, the reflectors 40 will be squarely facing the streets leading into the intersection so that the traffic lights 60, 61, and 62 may function to control the traffic. The reflectors 39 will be disposed at 45° to the path of travel of traffic moving from the streets into the intersection. It is, therefore, apparent that a motorist, moving in the direction of the arrow A (Fig. 13), will be able to see any vehicles back of him by means of the reflector 40 which faces him, and will be able to see any vehicles at B or C by means of the reflectors 39 which flank the aforesaid reflector 40. The several reflectors 39 and 40 will, of course, be adjusted to effect such a result and this ability to see the cross traffic, even where a light is controlling the traffic, is highly advantageous at those intersections where buildings obstruct the view, inasmuch as a motorist traveling with the green light will be able to see a fire engine, ambulance, or the like, which is approaching the red signal. It is a well-known fact that motorists drive in the winter time with the windows substantially closed, rendering it impossible to hear the sirens and bells of fire engines, ambulances, and the like. It is apparent, therefore, that the present traffic signal involves a high safety factor.

45 50 The lights 64, which are disposed beneath the reflectors 39 and 40, can be adjusted to play upon any hazards in the neighborhood of the traffic signal 20, such as the intersecting curb stones, a broken place in the street, and the like. These lights can be properly screened to prevent blinding of motorists.

55 60 The light disposed within the reflector 36 finds particular use in "spotting" a traffic officer standing beneath the traffic signal 20 directing traffic during trouble with the signal lights. Even the best of traffic signals are inoperative at times due to the wear of the working parts, and the like.

65 70 It is apparent that the traffic signal 20 may be other than octagonal in shape. In Fig. 14, there is diagrammatically shown a traffic signal of a configuration to adequately control a three-way intersection. A traffic signal suitable for the control of traffic moving into a five- or six-way intersection would include ten and twelve sides, respectively.

75 80 It is apparent that there has been provided a traffic signal which is adapted to fulfill all of the objects and advantages sought therefor. It is to be understood that the foregoing description

and accompanying drawings have been given by way of illustration and example and not for purposes of limitation, the invention being limited only by the claims which follow.

What is claimed is:

1. A traffic device comprising means for supporting said traffic device above the street in the intersection, a shaft connected to the supporting means, a plurality of clear reflectors supported by the shaft in spaced relation thereto forming a polygonal periphery, said reflectors providing means for a motorist approaching the intersection to determine the traffic on the intersecting streets and on the street on which he is moving.

2. A traffic device comprising means for supporting said traffic device above the street in the intersection, a shaft connected to the supporting means, a plurality of clear reflectors sup-

ported by the shaft in spaced relation thereto forming a polygonal periphery, said reflectors providing means for a motorist approaching the intersection to determine the traffic on the intersecting streets and on the street on which he is moving, and means for adjusting the reflectors to secure proper image focus.

3. A traffic device comprising a shaft, means for supporting said shaft, a member connected to and disposed about said shaft, said member having a polygonal periphery, and a clear reflector mounted on each side of the polygonal periphery, each reflector being mounted for universal adjustment, one reflector being disposed at right angles to each street, and one reflector being disposed at forty-five degrees between adjacent intersecting streets.

HENRY W. DODSON.
